DESIGN FOR A PLANING-MACHINE FRAME.

59,421.

specification for Design.

Patented Oct. 18, 1921.

Application filed November 5, 1920. Serial No. 422,056. Term of patent 14 years.

To all whom it may concern:

Be it known that I, IRA T. HOWARD, a citizen of the United States, residing in the city of Canton, county of Stark, Ohio, have invented a new, original, and ornamental Design for a Planing-Machine Frame, of which the following is a specification, reference being had to the accompanying drawing, forming a part hereof.

On the drawing, the single figure, which is

a perspective view of the machine, clearly illustrates and shows my new design for a planing machine.

I claim:

The ornamental design for a planing machine frame, as shown.

In testimony whereof I have hereunto affixed my signature this 29th day of October, 1920.

IRA T. HOWARD.
